United States Patent Office.

JOHN GRINDROD, OF ALBANY, NEW YORK.

Letters Patent No. 100,751, dated March 15, 1870.

IMPROVEMENT IN COPING FOR WALLS.

The Schedule referred to in these Letters Patent and making part of the same.

To all whom it may concern:

Be it known that I, JOHN GRINDROD, of Albany, in the county of Albany, and State of New York, have invented a new and improved Cast-Iron Coping for Walls; and I do hereby declare that the following is a full, clear, and exact description thereof, which will enable others skilled in the art to make and use the same, reference being had to the accompanying drawings forming part of this specification.

This invention relates to copings for walls, and consists in certain improvements on those now known to the public, which will be specified hereinafter.

Figure 1 is a transverse section of a wall provided with my improved coping;

Figure 2 is a longitudinal section; and

Figure 3 is a side elevation of the same.

Similar letters of reference indicate corresponding parts.

A represents the coping-plates, made in short sections, with downward-projecting flanges B at each side, and with the transverse caps C at one end, and the transverse vertical flanges E at the other; also, with the short flanges F at each side for connecting the ends of the sections together by bolts G.

The vertical transverse flange and the cap C are to form a joint which will not admit water and snow. The cap is made broad enough to allow for expansion and contraction of the metal, and the space H between the flange E and the wall I of the cap may be packed with elastic substance, which will close it, but will yield to the changes of the metal. These copings may be flat, oval, or of other approved form on the top, suitable for walls of any width, and cast in convenient lengths.

The flanges E extend across the top only, but the caps C extend down the sides as far as the flanges B do, and the flanges F fit against the sides of the wall and assist to hold the copings, which are imbedded in mortar, upon the walls more firmly than would be the case without them.

When this coping comes in contact with chimneys or against a building higher than the wall on which they are, the chimney or wall may be built upon the flange E so as to project slightly, and make a watertight and permanent finish, the ends to which the flanges E are attached being always arranged against the said walls or chimneys.

These copings are intended as a substitute for the common wood copings, which are exposed to fire, also to decay by the action of the weather. They also work loose by warping, and admit the water, and disturb and break the top of the wall by the movements caused by warping; whereas these retain their places, are much more durable, and cost but a trifle more than those made of wood. They may also be more ornamental. They should be coated with paint for protection against corrosion.

Having thus described my invention, I claim as new, and desire to secure by Letters Patent—

A coping made of short sections A, having flanges B, transverse caps C, vertical flanges E, and short flanges F, all combined, constructed, arranged, and adjusted as and for the purpose specified.

JOHN GRINDROD.
